SELF-ENERGIZING ELECTROLYTIC COR-
ROSION PREVENTING DEVICE

Ual J. Brown, Oklahoma City, Okla.

Application November 25, 1946, Serial No. 712,127

2 Claims. (Cl. 204—248)

1

This invention relates to corrosion and scale preventing devices and more particularly to a self-contained electrochemical device for preventing the deposition of scale, corrosion and the like in radiators and engine cooling systems.

It is well known that the agitation and heat present in the solutions circulating through radiators and engine cooling systems cause the precipitation of calcium sulphates, and other materials from the water. Chemical and electrolytic action may be set up in the cooling system which corrodes the exposed surfaces thereof. This is particularly true in warm weather where the cooling liquid is relatively high in temperature. Many of these incrustations are hard adhering scale which is very difficult to remove and often stop flow through the radiator or cooling system. Chemical treatment is sometimes used to remove the scale and corrosion particularly from motor car cooling systems, however, usually the chemical includes an active agent that is deleterious to the metal of the radiator and cooling system and sometimes such treatment results in leaks in the cooling system.

The principal objects of the present invention are to provide a self-contained all-metal electrolytic device for use in a cooling system in such a manner that water in the system passes around and through said electrolytic device; to provide a zinc alloy sacrificial element in a corrosion preventing device; to provide an all-metal electrolytic device of dissimilar metals, one consisting of an electro-negative element with respect to iron and the other an electro-positive element with respect to iron, which when placed in the water of a cooling system generates a slight electric current; to provide an electrolytic device of dissimilar metals wherein an element of metal such as zinc acting as a negative electrode is supported in a barrel formed of metal such as copper acting as a positive electrode; to provide a self-contained electrolytic device of dissimilar metals with members for mounting said device in a radiator hose connection between a radiator and engine; to provide for mounting an electrolytic device of this character in a cooling system duct in spaced relation to the walls thereof; to provide an electrolytic device that will perform successfully in any conventional brand of antifreeze used in engine cooling systems; to provide resilient members on a self-contained electrolytic device for mounting same in a cooling system; to provide a resilient mounting for the sacrificial elements in an electrolytic device; and to provide a corrosion and scale preventer of this character which is simple

2

in construction, efficient in operation, economical to manufacture and readily installed in a cooling system.

In accomplishing these and other objects of the present invention, I have provided improved details of structure, the preferred form of which is illustrated in the accompanying drawings, wherein:

Fig. 1 is an elevational view of a corrosion and scale preventer embodying the features of the present invention, the unit being shown mounted in a radiator hose connecting a radiator with an engine cooling system.

Fig. 2 is a perspective view of the self-contained electrolytic device.

Fig. 3 is a longitudinal section through the electrolytic device supported in a radiator hose.

Fig. 4 is a longitudinal sectional view through the electrolytic device with the resilient mounting members arranged to permit the device to be installed in short lengths of radiator hose.

Fig. 5 is a transverse sectional view through the electrolytic device illustrating the shell as plated with a metal lower in the electrochemical series.

Referring more in detail to the drawings:

1 designates a corrosion and scale prevention device consisting of dissimilar metals adapted to be immersed in the cooling liquid in an engine 30 cooling system, and preferably mounted in a hose connection 2 of an engine 3 and radiator 4. As illustrated in Fig. 1, the engine 3 is preferably provided with a water pump 5 having an inlet 6 connected by a hose 7 with the lower end of the radiator 4, whereby operation of the engine will cause water to be drawn from the lower part of the radiator and forced upwardly through the engine to a connection 8 at the upper end thereof, said connection being connected with the upper portion of the radiator by means of the hose connection 2. In the illustrated instance the engine is provided with a fan 9 adapted to draw air through the radiator to cool the water passing therethrough. The engine and the radiator as 40 illustrated do not form any part of the invention other than illustrating a particular adaptation of the self-contained corrosion preventing device for protecting the radiator and cooling system from scale, rust and the like.

The corrosion preventing device 1 consists of dissimilar metal electrodes, the positive electrode preferably being in the form of a tubular shell 10, circular in cross-section and smaller in diameter than the hose connection 2 or other space in which the device is to be mounted whereby free

flow of water may be had around the device. The shell 10 is of such length that it may be conveniently placed in a conventional radiator hose 2 and be entirely contained in the length thereof between the engine and radiator connection. Located adjacent the ends 11 and 12 of the shell 10 are diametrically opposite slots 13 and 14 and 15 and 16 respectively adapted to receive resilient members 17 and 18 for supporting a negative electrode element 19 in the shell. The element 19 is preferably of zinc and the shell of copper or brass. The element 19 may be of any cross-sectional shape, however, it is preferably square as illustrated, and is slightly longer than the spacing between the outer edges of the slots 13 and 15, the ends 20 and 21 of said element 19 being provided with threaded apertures 22 and 23 adapted to receive screws or like fastening devices 24 preferably of the same material as the material of the shell 10 for securing the members 17 and 18 to the negative electrode element 19 for supporting said element preferably in coaxial relation with the shell 10.

The members 17 and 18 preferably consist of strips of spring brass of a width permitting insertion through the slots 12 and 14 and 15 and 16. The central portions of the members 17 and 18 form bars 25 extending diametrically across the shell 10 and engage the ends 20 and 21 respectively of the element 19, the apertures 26 and 23 being arranged in the bar portions 25 to receive the screws 24 for insertion into the element 19. The portions of the members 17 and 18 extending outwardly from the slots 13 and 14 and 15 and 16 are preferably bent as at 27 in close proximity to the wall of the shell 10 whereby the bends will prevent lateral movement of the bars 25, thereby maintaining the element 19 substantially on the axis of the shell 10. The bends 27 preferably are arranged whereby the ends of the members 17 and 18 extend toward the ends of the shell 10 forming fingers 28 adapted to engage the walls 29 of a hose connection 2 or other duct of the cooling system. In order to facilitate movement of the device into a hose connection, the outer ends of the fingers 28 are preferably curved as at 30 whereby no sharp edges will engage the walls of the hose connection. The fingers 27 may also be bent as at 31 to arrange the angularity of the fingers 28 with the wall 29 of the hose connection to obtain the proper resiliency for a firm mounting of the electrolytic device therein. It is obvious that the members 17 and 18 being formed of spring brass will permit bending of said member to adapt the spacing of the fingers 28 to fit various size hose connections and provide proper resiliency for positively anchoring the device therein.

The form of the device shown in Fig. 4 is substantially the same as that in Fig. 3, except that the fingers 28 are bent as at 32 adjacent the shell 10 and backwardly alongside the shell. The ends of the fingers are curved as at 33 to engage the wall 29 of a hose connection 2. This arrangement of the mounting member permits the electrolytic device to be inserted in shorter lengths of hose connections than the form shown in Fig. 3. It is believed obvious that the fingers as shown in Fig. 4 may be bent in the same manner as the fingers in the form shown in Fig. 3 to adjust the device to fit various sizes of hose connections.

It is to be noted that the dissimilar elements 10 and 19 are arranged in spaced relation and such dissimilar metals when so arranged and placed in a liquid containing foreign particles,

salts, or compounds of such to act as an electrolyte, set up a slight current of electricity providing corrosion protection for the metal through which the water flows.

In assembling a corrosion and scale prevention unit of the character described, the member 17 is inserted through the slots 13 and 14 and bent as at 27 whereby the fingers 28 are of equal length, said fingers being bent to any angularity to adapt same for engagement in a hose connection 2. With this arrangement the aperture 26 in the bar 25 of said member 17 is preferably coaxial with the shell 10. The element 19 is then placed in the shell 10, the aperture 22 being in alignment with the aperture 26. A screw or other fastening device 24 is then inserted through the aperture 26 and into the aperture 22 to anchor said element 19 to the bar 25. The member 18 is then placed through the apertures 15 and 16 while pressure is applied to the element 19 to force same toward the end 11 of the shell 10 against the resiliency of the member 17 first applied to the device. The member 18 is arranged with the aperture 26 therein in alignment with the aperture 23 of the element 19. The fastening device 24 is then inserted through the apertures to anchor the element 19 to said member 18. The member 18 may then be bent as at 27 adjacent the wall of the shell 10 to hold the negative electrode element 19 substantially coaxial with the positive electrode on shell 10, the ends of the members 17 and 18 being shaped to provide fingers 28 of proper spacing to resiliently engage a hose connection or other suitable duct in the engine cooling system.

The electrolytic device may be applied to the cooling system by loosening hose clamps 36 on the hose connection 2 and removing said hose from either the connection member 8 or the radiator. The electrolytic device 1 may then be inserted in the hose and said hose replaced on the connecting member 8 and radiator, the clamps 36 being tightened to hold same in assembled condition. The device is then ready for operation and will provide only slight resistance to free flow of liquid through the hose connection.

The operation of the corrosion and scale prevention device after it is placed in the hose connection and cooling liquid placed in the system is as follows. An electric current flows from one element to the other and the negative electrode 19, will be gradually disintegrated by chemical action. The current of electricity created by the self-contained scale prevention unit not only prevents formation of scale on the metal of the equipment, but also causes the fluid flowing through the metal members of the equipment to slowly dissolve the scale formations that are present thereon, thereby preventing stopping of flow through the equipment and eliminating leaks and breakage through corrosion.

While I have particularly illustrated and described a self-contained corrosion and scale prevention device adapted to be placed in a hose connection or the like in a radiator and engine cooling system, it is obvious that the invention is adapted for other uses where water containing solutions of various compounds of lime, sulphate and the like are found in which there are possibilities of scale or deposits forming on metal parts of the equipment.

From the foregoing it is apparent that I have provided a self-contained and self-energized

electrolytic device for preventing corrosion and removing and preventing scale formations on the metal parts of equipment having water or like liquid and it is also apparent that the structure is particularly adapted for economical manufacture and facile installation and is not subject to breakage of the elements or other premature deterioration.

What I claim and desire to secure by Letters Patent is:

1. A self-energizing electrolytic apparatus for installation in a hose connection of a radiator and engine cooling system comprising a tube composed of metal constituting a positive electrode, said tube being open at each end, resilient strips extending across and engaging said tube adjacent the ends thereof and terminating in resilient fingers adapted to engage the wall of the hose connection for supporting the apparatus therein, said strips having bent portions lying alongside the tube for preventing transverse movement of said strip relative to the tube, a bar of metal constituting the negative electrode arranged in the tube and in concentric spaced relation thereto, said resilient strips being fastened to and supporting the ends of the bar.

2. A self-energizing electrolytic apparatus for installation in a hose connection of a radiator and engine cooling system comprising, a tube composed of metal constituting a positive electrode, said tube being open at each end and having diametrically opposed apertures adjacent each end thereof, resilient strips extending transversely of the tube and through said apertures,

said strips having bends exteriorly and adjacent said tube forming portions lying substantially alongside the tube and terminating in diverging fingers for resiliently engaging the wall of the hose connection for supporting the apparatus therein, said bends substantially preventing transverse movement of the resilient strips relative to the tube, a bar of metal shorter in length than the tube and constituting the negative electrode arranged in the tube and in concentric spaced relation thereto, said resilient strips being fastened to and supporting the ends of the bar.
